ATTORNEY.

UNITED STATES PATENT OFFICE

115,395

DESIGN FOR A GLASS FRYING PAN

John G. Francis, Chicago, Ill., assignor to Chamberlain, Inc., Chicago, Ill., a corporation of Illinois

Application November 12, 1938, Serial No. 81,035

Term of patent 7 years

To all whom it may concern:

Be it known that I, John G. Francis, a citizen of the United States, residing at Chicago, Cook County, Illinois, have invented a new, original, and ornamental Design for a Glass Frying Pan, of which the following is a specification, reference being had to the accompanying drawing forming part thereof.

In the drawing:

Figure 1 is a side elevational view of a glass frying pan, showing my new design;

Figure 2 is a top plan view; and

Figure 3 is an end elevational view thereof.

I claim:

The ornamental design for a glass frying pan, as shown.

JOHN G. FRANCIS.
